SAFETY LOWERING AND CONTROL MECHANISM FOR WINCHES AND THE LIKE

Charles C. Martin, Cleveland Heights, Ohio, assignor to David Round & Son, Garfield Heights, Ohio, a firm

Application August 1, 1944, Serial No. 547,577

3 Claims. (Cl. 254—186)

This invention as indicated relates to a safety lowering and control mechanism for winches and the like. More particularly, it comprises an automatically acting mechanism which permits progressive releasing or lowering action under full control of the operator.

In operating winches the lowering movement usually involves separate braking mechanism which is subject to excessive wear with possibility of complete failure, or at least overrunning with heavy damage or injury to the load or operatives. In the present invention the load automatically applies the braking or checking force and the operator sets the rate of control or braking action. This is preferably accomplished by the same means used in manually lifting the load, the reversing of the motion of the hand-crank controlling both the degree of lowering movement and the speed with which it takes place.

The principal object of the present invention is to provide a safety lowering and control mechanism for winches and the like.

Another object of the invention is to provide a single lifting and lowering mechanism for winches and the like which will be dependable in action and of long service life.

Another object of the invention is to provide an improved winch structure particularly suited for manual operation which will at all times be under control during both the hoisting and lowering operation.

Another object of the invention is to provide a winch with load-actuated braking means of small size and high capacity responsive to releasing control of the operator with unusual precision and yet operating smoothly and without shock.

Other and further objects of the invention will appear in the course of the following description.

To the accomplishment of the foregoing and related ends, said invention, then, consists of the means hereinafter fully described and particularly pointed out in the claims, the annexed drawings and the following description setting forth in detail certain mechanism embodying the invention, such disclosed means constituting, however, but several of various forms in which the principle of the invention may be used.

In said annexed drawings:

Fig. 1 is an enlarged central vertical sectional view showing the operative features of the invention, with associated parts shown in full lines, as seen along the line 1—1 shown in Figure 2;

Fig. 2 is a fragmentary end elevation of a portion of the structure shown in Figure 1;

Fig. 3 is an end elevation of a winch structure

provided with a safety lowering and control mechanism embodying the features of the invention; and

Fig. 4 is an elevation of the winch structure as seen from the right-hand side of Figure 3.

The safety lowering and control mechanism as applied to a manually operated winch comprises a unit 1 associated with a pinion 2 adapted to be engaged with a gear 3, or gear train, of a winch 10 or similar structure. The pinion 2 is carried on a shaft 4 having its free end 5 engaged in a suitable bearing on the winch frame and held therein by a latch element rotatably engaging the annular recess 6. The opposite end 7 of the shaft 4 is of reduced diameter and provided with a keyway 8 by means of which a tubular hub 9 formed integrally with a braking disc 11, is non-rotatably held on said shaft by a suitable key engaging said keyway. The tubular hub 9 is provided with a heavy 20 duty right-hand screw-thread 12 engaging in a screw-threaded opening 13 in the hub 14 of a movable brake-actuating member 15.

The brake-actuating member 15 has a range of endwise movement provided by said screw-threaded engagement on the tubular hub 9. It is held from disengagement from the hub 9 in one direction by the abutment plate 16 held by a castellated nut 17 on the reduced screw-threaded end 18 of the shaft 4, which is locked by a cotter pin 19.

30 The inner face of the braking disc 11 provides a surface against which an annular friction member 21 is engaged, said friction member being housed in a recess in the adjacent face of a floating braking disc 22, having a rearwardly-projecting tubular hub 23 rotatably engaged over a reduced terminal portion 24 of the endwise movable 35 brake-actuating member 15. The hub 23 engages a circular recess 26 formed in the adjacent end face of the disc portion 27 of the brake-actuating member 15.

40 The disc 27 abuts the floating braking disc 22 through a perforated brass free friction annular member 28 interposed between said adjacent disc surfaces and pivotally supported on the thin extension flange 25.

45 The floating braking disc 22 is provided on its outer circumference with an overhanging flange 31 formed with ratchet teeth 32, engageable by a spring pressed pawl 33 pivotally mounted on the adjacent winch frame 34.

50 A recessed cap member 35 is bolted to spokes 36 on the brake-actuating member 15 and engages in spaced relation over the abutment plate 16 and nut 17. The cap member carries centrally of its end face an integral stub shaft 37 over

which the hub portion 38 of the hand-crank 39 may be engaged. For movement of the winch without a load the hand-crank 39 may be engaged on the main shaft 41 of the large gear 3.

For extra heavy duty the lowering and control unit 42 which is substantially identical in its operative elements with unit 1 may drive the drum 43 of hand winch 44 through a series of reduction gears 45 as shown in Figures 3 and 4. It will be noted that the pawl 46 is applied to a member 47 of the gear train. The crank shaft may be applied to the stub shaft 48 for safety lowering and control, and to the shaft end 49 for movement of the mechanism rapidly without a load.

The operation of the winch has been suggested in connection with the description of the parts. The hoisting operation is carried on by turning the crank in a clockwise direction causing the cap member 35 to turn the brake-actuating member 15 on its screw-threaded support and press the disc 27 against the annular friction member 28 which bears against the floating braking disc 22 forcing it into compressive engagement with the friction member 21 pressing on the fixed braking disc 11 keyed to the pinion shaft 4. The pinion is in driving engagement with the drum of the winch and hoisting action takes place.

To bring about lowering movement of the load the crank handle 39 is moved reversely. This relieves the pressure of the brake-actuating member, moving transversely on its screw-threaded support, on the floating braking disc 22 which is held from rotation counter-clockwise by the pawl 33, and all the friction elements move outwardly away from the shaft supported braking disc 11.

As the braking disc 11 turns counter-clockwise with the pinion shaft the load will be lowered, but the lowering operation turns the tubular hub 9 with its screw-thread 12 which movement tends to draw the friction elements of the unit into braking engagement. However, continued movement of the screw-threaded member 13 to releasing position again tends to separate the friction elements, and so long as the rate of separating movement of the outer screw-threaded element of the pair exceeds the rate of movement of its companion inner screw-threaded element there will be no reengagement of the friction elements and the load will continue to be lowered. By controlling these members so as to bring about partial frictional engagement the lowering rate can be controlled with a high degree of precision.

Other modes of applying the principle of my invention may be employed instead of those explained, change being made as regards the mechanism herein disclosed, provided the means stated by any of the following claims or the equivalent of such stated means be employed.

I therefore particularly point out and distinctly claim as my invention:

1. In an apparatus of the character described a frame, a drum rotatably supported on said frame, a load carrying cable engaged over such drum, a power multiplying mechanism associated with said drum for actuating the same and elevating the load on said cable when moved in one direction of rotation, comprising a pinion carrying a disk and a screw shaft, a crank operated clamping member movably mounted on said screw shaft and provided with an extension hub, a ratchet disk rotatably mounted on the hub of said movable clamping member intermediate the same and said disk, a pawl pivotally mounted on said frame in operative relation to said ratchet disk, a hub bearing provided on said ratchet disk, a free perforated friction disk mounted on said hub bearing, said clamping member adapted to move said parts into engagement for elevating the load for lowering said load under frictional braking control at a speed proportional to the movement of said power multiplying mechanism through rotation in the reverse direction.
2. A winch, comprising a frame, a drum rotatably supported in said frame, gear and pinion means for driving said drum, a braking disk and screw threaded member operatively connected with said pinion, a screw threaded sleeve having an extension hub and a clamping disk mounted on said screw threaded member, a hollow housing engaging over said screw threaded member and connected with said screw threaded sleeve for operating the same, a crank arm releasably mounted on a projection of said hollow housing, a ratchet disk rotatably mounted on said hub intermediate said braking disk and clamping disk, and a pawl pivotally mounted on said supporting frame for operatively engaging said ratchet disk.
3. A winch comprising spaced apart base supported frames, a drum journaled between said frames, a driving gear outside of one of said frames operatively connected to said drum for actuating the same, a safety lowering and control mechanism associated with said gear and frame comprising a shaft journaled in said one frame and having an integral pinion engaging said gear, a braking disk having a longitudinally extending screw threaded hub fixed on said shaft, a clamping member mounted on said hub having complementary screw threads for engaging with the screw thread of said hub, a floating braking disk between said braking disk and clamping member, said clamping member having an annular extending bearing portion for journaling said floating braking disk, said floating braking disk being provided with ratchet teeth on its circumference, a pawl pivotally mounted on said one frame for engaging said ratchet teeth, a housing on said clamping member for enclosing one end of said shaft and being provided with a projection for releasably mounting a hand crank.

CHARLES C. MARTIN.
